CONTAINER

George F. Ford, Beverly Hills, and Walter F. Pittman, Huntington Park, Calif., assignors to Fibreboard Products Inc., San Francisco, Calif., a corporation of Delaware

Application February 25, 1935, Serial No. 7,946

9 Claims. (Cl. 229—28)

Our invention relates to containers for holding eggs, and more particularly to containers comprising separately formed cartons and fillers.

It is among the objects of our invention to provide a container which affords better support and more protection for the eggs, yet which exposes a large portion of the eggs for display purposes.

Another object of our invention is to provide a filler construction which is folded from a single piece, and adapted to collapse flat for shipping.

Another object of our invention is to provide a collapsible filler which may be readily set up.

Still another object of our invention is to provide a filler which when set up is a rigid, self-supporting unit, and which does not depend upon the carton to hold its shape.

A further object of our invention is to provide a filler which places the load directly on the bottom of the carton, instead of transmitting it to the side walls.

A still further object of our invention is to provide a filler construction which readily permits and assists in the closing of the carton lid.

A still further object of our invention is to provide a filler which forms a crown top on the carton.

The invention possesses other objects and features of advantage, some of which, with the foregoing, will be set forth in the following description of our invention. It is to be understood that we do not limit ourselves to this disclosure of species of our invention, as we may adopt variant embodiments thereof within the scope of the claims.

Referring to the drawing:

Figure 1 is a perspective view of the container embodying our invention, portions of the carton being broken away to disclose the filler construction more clearly.

Figure 2 is a vertical sectional view of the container; and

Figure 3 is a plan view showing the blank from which the filler embodying our invention is folded.

Figure 4 is an end view of the blank showing the manner in which the same is folded into collapsed position.

Figure 5 is an end view of the filler in collapsed position. The filler is shown opened somewhat from the fully collapsed position to illustrate the manner of folding.

In terms of broad inclusion, the container embodying our invention comprises a separately

formed carton and filler. The egg holding filler is formed from a one-piece blank of sheet material, and from the blank is partially folded to a flat collapsed position convenient for shipping. From the partially folded collapsed position the filler may readily be completely folded to the final set-up condition. In the set-up position the filler comprises an inverted Y-shaped section and a plurality of inverted V-shaped sections straddling the Y-shaped section. The legs of the V-shaped sections are secured at their lower ends to the base of the Y-shaped section, and means are preferably provided for interlocking the intermediate portions of the V-shaped sections to the ridge of the Y-shaped section.

In greater detail, and referring particularly to Figures 1 and 2 of the drawing, the container embodying our invention comprises an outer carton having a bottom wall 2, side walls 3 and end walls 4. The carton is preferably rectangular in shape, the one shown being elongated and of the type designed for holding one dozen eggs in two rows of six eggs each. The carton is also provided with a cover or lid 6 and a cover flap 1 for holding the lid in place. The carton is also preferably provided with leg flanges 8 for supporting the bottom of the carton above the base upon which the carton rests.

As best shown in Figure 2, the sides of the carton preferably slope inwardly toward the bottom, so that the width across the top of the carton is greater than that across the bottom. This construction keeps the side walls spaced when the cartons are placed side by side.

As shown in Figures 1 and 2, the filler as finally set up and adapted for insertion in the carton comprises an inverted Y-shaped section 9 extending longitudinally of the carton and dividing the latter into two troughs, and also comprises a plurality of inverted V-shaped sections 11 straddling the Y-shaped section 9 and extending transversely of the carton for dividing the troughs into separate pockets. The inverted Y-shaped section of the filler comprises a vertically extending and centrally disposed ridge portion 12 of double sheet thickness, the sheets of which divide at the bottom of the ridge and diverge downwardly to form the legs 13. These legs form resilient suspensions for the eggs 14.

The lower portions of the legs 13 are flattened out into horizontally disposed and outwardly extending base portions 16 which rest against the bottom 2 of the carton. As best shown in Figure 2, the lower ends of the legs 13 terminate at points spaced inwardly from the side walls 3 of

the carton, and flat base portions 16 extend outwardly to the side walls. The flat base portions 16 provide bottom seats against which the points of the eggs may rest, and the arrangement is such that the weight of the eggs is carried substantially entirely by these base portions of the filler, the outward thrust against the sidewalls exerted by the eggs being very small.

The V-shaped sections or partition elements 11 each have a pair of wide leg portions 17 straddling the ridge portion 12 and extending downwardly into the parallel troughs formed by the body section, thereby dividing the troughs into a series of separate egg holding pockets. These leg portions 17 of the partition elements have their inner edges 18 spaced from the leg portions 13 of the body section to keep the portions 13 from bracing up against the edges 18. This provides a free suspension for the eggs. The partition legs 17 are also provided with substantially straight outer edges 19 extending upwardly along the side walls of the carton.

Partition sections 11 have their lower ends fixed to the base portions 16 of the body section. By this fastening the inverted Y-shaped body section is rigidly and securely held against spreading. The inverted Y-shaped body section is also suspended from the mid portions of the partition sections. This fastening also holds the partition elements in upright position. The fastening is preferably effected by a suitable interlock, such as an aperture 20 in the partition section 11 engaged by a hook 21 formed in the ridge portion 12 of the body section. In order to further prevent the body section from bracing rigidly against the partition elements, the body section is cut away about the hooks 21 to provide free spacing between the body and partitions. Note Figure 1. By this arrangement the upper portion of the body section is free of the partitions, except for the hook suspension.

The fact that the filler finds its principal support on the bottom 2, insures that the load is carried directly on the bottom of the carton, and not transmitted to the side walls. This is important in a carton of the character described having integrally formed flange portions 8, because in such a construction a side thrust would tend to split the legs.

As also shown in Figure 2, the ridge portion 12 of the body section terminates below the upper rim of the side walls. This insures a maximum exposure of the eggs for display purposes. It will also be observed that the upper side edges 22 of the partition sections are sloping and cut back to also aid in giving a maximum of egg exposure, yet without sacrificing protective value or rigidity of support. Another point of merit is the double sheet thickness at the ridge portion 12, which is the dividing element between the eggs of separate troughs. The sheets of this ridge portion are bowed out slightly to provide a resilient pad between the eggs.

As also best shown in Figure 2, the partition sections 11 preferably extend above the carton side walls to provide a raised central support for the cover 6 of the carton. This raised support causes the cover to assume an arched or crown shape, and not only gives additional spacing above and therefore added protection to the underlying eggs, but also provides an added support for the elevated bottom of an overlying carton when the cartons are in stacked relation. Another feature of the filler construction is that it has no side walls to interfere with the insertion of the cover

flap 7. The insertion of the cover flap is further aided by the sloping upper edges 22 of the filler, and also by the position of the eggs 14.

Another point of merit lies in the positioning of the eggs. The tilting of these eggs in our filler improves the display, and also adds a protective feature. The added protection is due to the fact that the tilted position throws the points of the eggs toward the lower side and the butts of the eggs to the upper center. By this arrangement the eggs in overlying cartons cannot contact because the butts and points are not in alignment. The eggs of cartons which are positioned side by side cannot contact because of the shape of the cartons, that is the sloping side walls cause the cartons to abut along their upper side edges and are held spaced along their lower side portions.

The filler embodying our invention is designed to be folded from a single piece of sheet material, and is adapted to collapse flat for shipping. Figure 3 shows the blank from which the filler is folded. The blank is generally rectangular in shape and comprises two portions, one of which forms the Y-shaped or body section and the other of which forms the V-shaped partition sections. As illustrated in Figure 3 the right-hand portion of the blank is cut to provide a series of V-shaped tabs.

These tabs form the partition sections 11 of the filler, and when lying flat and in the plane of the blank are nested together. This portion of the blank is also creased along substantially parallel and longitudinally extending lines 23 arranged along the side edges of the tabs 11, and is also creased along a plurality of transverse lines 24 extending across the base of the tabs. A longitudinal crease line 25 is also provided through the center of the tabs. This crease line is utilized when folding the filler into collapsed position for shipping.

The other portion of the blank is creased along a plurality of longitudinally extending and substantially parallel lines 26, 27 and 28. This portion of the blank is adapted to be folded so that the strip areas between the central crease line 26 and intermediate crease lines 27 form the ridge portion 12 of the inverted Y-shaped body section, and the strip portions between the intermediate crease lines 27 and outer crease lines 28 form the legs 13 of the Y, while the outer strip areas form the base portions 16. Suitable apertures 29 are cut in the blank so that when the latter is folded the hooks 21 are formed in the ridge portion 12 of the body section.

The forming of the blank and the folding thereof into collapsed position for shipping is as follows: As the sheet material comes from a supply roll it is scored to provide the longitudinal crease lines 23, 25, 26, 27 and 28, and transverse crease lines 24. The sheet is then cut to form the V-shaped partition sections 11, and next punched to form the various apertures. Simultaneous with this punching operation the blanks are severed from the main body of the sheet.

The completed blank, as shown in Figure 3, is then passed to suitable folding devices where the tabs 11 are folded in half along the crease line 25 and upwardly from the blank along the crease lines 23. Also the ridge portion 12 is folded up from the blank from the crease lines 27. The blank at this stage of folding is illustrated in Figure 4. The next steps comprise folding down the up-folded portion 11 in the direc-

tion indicated by the arrow 31, and then folding the shorter portion 12 down in the direction indicated by the arrow 32. The outer portions of the blank are folded in along the crease lines 23 and 27 in the directions indicated by the arrows 33, and then glued along their overlapping edges, with the narrow strip 34 underneath.

When fully collapsed the filler is substantially flat and occupies little space while shipping. Figure 5 shows the filler opened somewhat from the collapsed position. It is to be noted that the portions of the filler likely to become damaged are folded within the body of the collapsed parcel and are therefore protected against injury. As illustrated, the filler in collapsed condition is in the nature of an envelope, the two halves of which comprise M-shaped sections.

Upon reaching the consumer the collapsed fillers may readily be set up by unfolding the partition sections 11 and forcing the ridge portion 12 inwardly and into interlocking engagement with partition sections.

We claim:

1. A filler comprising an inverted Y-shaped section having a vertically disposed and upwardly extending ridge portion and having horizontally disposed and outwardly extending base portions, and a plurality of inverted V-shaped sections extending transversely of the Y-shaped section, the V-shaped sections straddling said ridge portion and secured at their ends to said base portions.

2. A container comprising a carton having bottom and side walls, an inverted Y-shaped filler section in the carton, and a plurality of inverted V-shaped filler sections straddling the Y-shaped section and secured at their lower ends to base portions of said Y-shaped sections resting upon the bottom of the carton adjacent the longitudinal corners thereof, the partitions extending from the bottom to the top of the carton and providing arch-like braces extending above the Y-shaped section for supporting a cover extending across the top of the carton.

3. A container comprising a carton having bottom and side walls, an inverted Y-shaped filler section having horizontally extending base portions resting on the bottom of the carton, and a plurality of inverted V-shaped filler sections straddling the Y-shaped section and secured at their lower ends to the base portions of said Y-shaped section.

4. A container comprising a carton having bottom and side walls, an inverted Y-shaped filler section in the carton, and a plurality of inverted V-shaped filler sections straddling the Y-shaped section and secured at their lower ends to the base portions of said Y-shaped section, said V-shaped sections extending upwardly to a point above the side walls of the carton.

5. A container comprising a carton having bottom and side walls, an inverted Y-shaped filler section in the carton, and a plurality of inverted V-shaped filler sections straddling the Y-shaped section and secured at their lower ends to the base portions of said Y-shaped section, the ridge of the Y-shaped section being positioned below the rim of the carton side walls and the V-shaped sections extending upwardly to a point above the side walls.

6. A container comprising a carton having bottom and side walls, an inverted Y-shaped filler section arranged centrally of the carton with the legs thereof spaced inwardly of the carton side walls and having horizontal base portions resting on the bottom of the carton and extending outwardly to the side walls, and a plurality of inverted V-shaped filler sections straddling the Y-shaped section and secured at their lower ends to the base portions of said Y-shaped section.

7. A collapsible filler comprising a blank having a portion thereof creased for folding into an inverted Y-shaped section and a second portion cut and creased for folding into a plurality of partition sections, said blank being folded with the partition sections and portions of the Y-forming portion interfolded between other portions of the Y-forming portion.

8. A filler comprising an inverted Y-shaped section having a vertically disposed central ridge portion and horizontally disposed base portions connected to the ridge portion by inclined arm portions, and a plurality of inverted V-shaped partitions extending transversely of the Y-shaped section and straddling the ridge thereof, said partition having diverging arms seating upon the base portions, the inner and outer edges of the diverging arms being substantially parallel to the inclined arm portions of the Y-shaped section and the upper portions of the partitions extending above the upper edge of the ridge portion.

9. A filler comprising an inverted Y-shaped section having a vertically disposed central ridge portion and horizontally disposed base portions connected to the ridge portion by inclined arm portions, and a plurality of inverted V-shaped partitions extending transversely of the Y-shaped section and straddling the ridge thereof, said partition having diverging arms seating upon the base portions, the inner edges of the partition arms being substantially parallel to and spaced from the inclined arm portions of the Y-shaped section, and the outer edges of the partition arms having inclined portions substantially parallel to the inner edges of the arms and extending to points above the upper edge of the ridge portion.
